UNITED STATES PATENT OFFICE.

EARLE P. PRESS, OF LAKE BLUFF, ILLINOIS.

REINFORCED-CONCRETE CONSTRUCTION.

1,348,445.

Specification of Letters Patent.

Patented Aug. 3, 1920.

Application filed June 2, 1917. Serial No. 172,367.

To all whom it may concern:

Be it known that I, EARLE P. PRESS, a citizen of the United States, and a resident of the village of Lake Bluff, in the county of 5 Lake and State of Illinois, have invented certain new and useful Improvements in a Reinforced-Concrete Construction; and I do hereby declare that the following is a full, clear, and exact description of the same, reference being had to the accompanying drawings, and to the numerals of reference marked thereon, which form a part of this specification.

This invention relates to a flat slab reinforced concrete construction wherein the reinforcement members leading into the columns from the floor panels are arranged in the most efficient manner to properly take care of the various stresses, whereby the 10 floor loads are transmitted directly to the columns and with the reinforcement members properly spaced in the forms and secured to one another to permit the concrete to be poured therearound without accidental 15 displacement of the reinforcement.

By this reinforced concrete construction, the loads upon the panels are carried direct to the column, instead of to a beam and then by way of the beam to a column. Furthermore, the elimination of beams and girders 20 from the ceiling is a great advantage increasing the lighting efficiency and facilitating attachment of equipment and other fixtures to the ceiling. The cost of erection of the 25 forms is cheapened and greatly simplified owing to the flat uninterrupted area of forms which may be constructed from standard lengths so that the greater part of the form work may be salvaged after the structure is completed. Owing to the fact that 30 the ceilings of the structure are unobstructed by beams or girders, the saving in the height of the building is considerable, as all 35 of the space between floors may be efficiently used, and this results in a saving in the cost 40 of erection of the building.

In monolithic concrete construction at the 45 point at which the flat slab or floor structure forms a part of the column, a negative bending moment exists in the area above the column, whereas in the floor panels between the column, a positive bending moment exists. The point at which the bend-

ing moment changes from positive to negative is termed the point of "contra-flexure," 55 and of course, it is desirable to properly dispose the reinforcement members of the structure so that the tension and the shear stresses are borne by the reinforcement members, and the compression stresses by the 60 concrete itself.

It is an object therefore of this invention to provide a reinforced concrete construction wherein the floor panel main reinforcement members near the junction of the columns 65 with the floor of the structure are bent at an angle, that is, at the point of shear or contra-flexure, and extend upwardly into the area of negative bending moment over the columns. 70

It is also an object of this invention to provide an improved form of reinforced concrete construction wherein the reinforcement members of the floor at the entrance into the column structure are properly 75 mounted upon supports provided for the purpose and held secure against accidental displacement during pouring of the concrete, and with the main reinforcement members bent so as to be disposed in the area subject 80 to tension due to the respective positive and negative bending moments existing in the structure, and with the angled portions of said reinforcement members disposed in the area of shear or contra-flexure of the structure. 85

It is also an object of this invention to provide a flat slab concrete construction wherein reinforcement members are properly bent for correct disposition in the structure, when formed, to properly take care of the various stresses, which are transmitted from the floor panels directly to the columns, and with means for supporting and connecting the reinforcement members to insure proper spacing and disposition thereof, 90 as well as to positively secure the same from accidental displacement when the concrete is poured, and further permitting the reinforcement to be rapidly fabricated by the 95 workmen.

It is a further object of this invention to provide a reinforced concrete construction wherein the series of secondary diagonal reinforcement members of the floor panels 100 intersect one another at the columns and

pass directly to and through the column head, and with the main reinforcement members extending directly from column to column and terminating in the column heads, 5 bent upwardly at their point of entrance into the column head, with their ends lying adjacent one another and the bent portions of said members disposed substantially at the point of contra-flexure in the flat slab at 10 the column.

It is furthermore an object of this invention to provide a reinforced concrete structure wherein certain of the secondary diagonal panel reinforcement members entering a 15 column pass directly therethrough and with others thereof terminating at the column, and with the main reinforcement members which terminate in the column heads bent upwardly at the point of entrance into the 20 column head disposed above said secondary members, and with the terminating ends of said main members laid adjacent one another and interlaced and properly spaced upon the form.

25 Other and further important objects of this invention will be evident from the disclosures in the drawings and specification.

The invention (in a preferred form) is 30 illustrated in the drawings and hereinafter more fully described.

In the drawings:

Figure 1 is a fragmentary top plan view 35 of the reinforcement members of a column head, utilizing means for support and spacing thereof embodying the principles of my invention.

Fig. 2 is a fragmentary central vertical section taken therethrough with parts omitted.

40 Fig. 3 is a plan view broken away of a head support for a column head.

Fig. 4 is a side elevation thereof.

Fig. 5 is a sectional detail taken on line 5—5, of Fig. 3.

45 Fig. 6 is a detail view illustrating the means of wiring two reinforcement rods crossing one another to the head support.

Fig. 7 is another detail view with the 50 head support in section illustrating means of wiring a reinforcement rod thereto.

Fig. 8 is a sectional detail on line 8—8, of Fig. 2, showing a pair of bar spacers engaging three adjacent rods.

As shown in the drawings:

55 The reference numeral 1, indicates as a whole the form for the column of a concrete structure, and the reference numeral 2, the form for the floor or horizontal panel beam system for the floor of the structure. In 60 the form of construction illustrated in Fig. 1, the main reinforcement rods are denoted by the reference numeral 3, and extend directly from column to column into the column heads and are bent upwardly and suitably supported as hereinafter described and

terminate therein with said terminating ends laid side by side. Secondary reinforcement rods are denoted by the reference numeral 4, and extend diagonally through the floor panels into the column head around the 70 lower portion thereof, terminating therein. The reinforcement rods 3, as they lead into the column head slightly beyond the point at which they are bent upwardly are supported upon a frame 5, consisting of a one 75 piece bar of metal or a plurality of bars arranged substantially in rectangular form, and forming a head support for the terminating ends of said main reinforcement members. Said head support 5, is apertured at a plurality of points and engaged therethrough are the bent ends of triangular supports or legs 6, which are of a height dependent upon the particular design of the structure in order to secure proper spacing 80 position of the head support 5, for the reinforcement rods 3, supported thereon. Said supporting legs 6, may be stapled to the form 2, as indicated by the reference numeral 7, and shown in Fig. 5, to secure the 85 same against accidental displacement. Also engaged through apertures in the head support bar 5, are a plurality of soft wires 8, the spacing of which has been predetermined by the design for the reinforcement so that 90 said wires may be used as shown in Figs. 6 and 7, to fasten the reinforcement rods 3, 95 securely upon the support frame 5.

The reinforcement rods 3 and 4, are all 100 supported in spaced relation upon the form 105 2, by bar spacers, each of which consists of a rod 9, one end of which is bent inwardly and downwardly as denoted by the reference numeral 10, to afford a recess and supporting leg for a rod 3, and the other end of 110 which is similarly bent inwardly and downwardly as denoted by the reference numeral 11, to afford a recess and supporting leg for another rod 3, whereby the rods 3, are supported spaced from one another and spaced 115 from the form, as clearly shown in Fig. 8.

The head supports are made up in the shop and sent to the job with the holes for the leg supports and fastening wires disposed at the proper interval for spacing of 115 all bars. The fastening wires 8, are generally inserted through the frame 5, at the shop for properly tying all the reinforcement bars in their correct position. The head support is spaced from the form by 120 the supporting legs 6, which are fastened to the form thus giving a rigid support for properly holding the reinforcement rods fixed in the upper port of the slab around the column head, and also acting as a spacer for 125 the reinforcing bars radiating from the column head.

I am aware that various details of construction may be varied through a wide range without departing from the principles 130

of this invention, and I therefore do not purpose limiting the patent granted otherwise than necessitated by the prior art.

I claim as my invention:

- 5 The combination with the reinforcement rods of a concrete structure, of a head support comprising an apertured frame, a plurality of wires bent to form triangular legs, the ends of which are hooked in the apertures of the frame, to support the frame with the reinforcement rods resting thereon, and wires engaged through other of said
- 10

frame apertures adapted to be passed around said reinforcement rods to hold the same secured to said frame and properly spaced.

In testimony whereof I have hereunto subscribed my name in the presence of two subscribing witnesses.
